UNITED STATES PATENT OFFICE.

BENJAMIN F. CARD, OF BROOKLYN, NEW YORK.

MOTOR.

SPECIFICATION forming part of Letters Patent No. 237,728, dated February 15, 1881.

Application filed June 29, 1880. (No model.)

To all whom it may concern:

Be it known that I, BENJAMIN F. CARD, of the city of Brooklyn, county of Kings, State of New York, have invented a new and useful Improvement in Motors, of which the following is a specification.

This invention relates especially to that class of motors in which the vapor of bisulphide of carbon is utilized to obtain a force or pressure.

It is a well-known fact that the material referred to is a powerful solvent of the oils or fats generally used for lubricating purposes, while it evaporates quickly at ordinary temperatures, and to these properties thereof is due mainly the failure of its successful introduction into use up to the present time. In other words, all motors permitting the use of a vapor, as of bisulphide of carbon, demand the liberal use of lubricants to overcome friction, or are productive of loss or waste by the escape of the vapor.

The general object of this invention is to obtain a motor adapted to the successful and economical use of the vapor of bisulphide of carbon—namely, by the combined effects of minimum friction and a maximum confinement of the vapor.

This invention is illustrated in the accompanying drawings, in which Figure 1 represents a vertical section. Fig. 2 is a plan or top view, partly in section. Fig. 2* is a detail view of the supply-valve. Fig. 3 is a horizontal section on the line $x-x$, Fig. 1. Fig. 4 is a similar section on the line $y-y$, Fig. 1. Fig. 5 is a vertical section of the vaporizing-chamber. Fig. 5* is a side view of the driving-wheel. Fig. 6 shows a modification of the core of the vaporizing-chamber, corresponding to Figs. 8 and 9. Fig. 7 is a detail view of the cut-off. Figs. 8 and 9 show a modification of the invention.

Similar letters of reference indicate like parts in all the figures.

The letter A designates a chamber, to which the bisulphide of carbon is admitted. For the admission of the bisulphide of carbon to this vaporizing-chamber A, I make use of a valve, B, which is arranged at the top of such chamber, and constructed with triple ways a , more or less, (see Figs. 2 and 2*,) whereby steam or atmospheric air, or both, may be admitted

alternately with the bisulphide of carbon. The shape of the vaporizing-chamber A is that of an annulus, and into the same is fitted a driving wheel or drum, C, which turns on a vertical axis, as hereinafter more fully described, and which is constructed, essentially, of a series of blades, bent or curved substantially similar to those of a turbine, such blades being connected together at the top and bottom by suitable heads or rings, with the spaces between them left open or vacant.

Communicating with the vaporizing-chamber A is a condenser, D, through which a stream of water or other liquid is kept running by means of pipes a' a' for the condensation of the vapor, while between the vaporizing-chamber and such condenser is interposed a cut-off, F. This cut-off consists of disks b b , one of which has ports b' , (see Fig. 7,) arranged in a circle concentric to the disk, while the other is constructed with gates b^2 for closing the ports. In the example shown the number of the gates b^2 is unequal to that of the ports b' , so that the two do not register with each other in any position of the cut-off disks, and it follows that the communication between the vaporizing-chamber A and condenser D is never entirely cut-off. If desired, however, the ports and gates b' b^2 may be so arranged as to be capable of registering with each other.

One of the cut-off disks b b constitutes the lower head or ring of the driving-wheel C, and hence it partakes of motion of such wheel, while the other disk is a fixture of the partition-plate between the vaporizing-chamber A and the condenser D, as shown in Fig. 1, so that it is immovable; or it is attached to the core G of the vaporizing-chamber, as shown in Fig. 8, where such core is movable or arranged to turn, as hereinafter more fully described.

Surrounding the vaporizing-chamber A is a heating-chamber, O, to which are connected pipes c c , for the admission and discharge of steam or other heating agent.

On the inner surface of the wall of the vaporizing-chamber A is formed a series of blades, d , which extend longitudinally thereto, or in vertical directions, and are radial to the axis of the driving-wheel C.

In the example shown in Fig. 1, the core G of the vaporizing-chamber is fixed, the same

- being secured to a rod, H, rising from the bottom of the condenser D, and the driving-wheel C is mounted on a shaft, I, projecting therefrom in opposite direction, the lower part of 5 such shaft being tubular, and being stepped in a block, d^o, at the base of the rod H, which latter passes through it, while the upper part of such shaft passes through a stuffing-box, e, at the top of the vaporizing-chamber.
- 10 In the example shown in Figs. 8 and 9 the core G of the vaporizing-chamber is secured to a shaft, I', while the driving-wheel C is mounted on gudgeons I², the lower one of which turns in a block, d', resting on the bottom of 15 the condenser D, and constitutes a step for the lower end of the shaft I', while the upper gudgeon is a fixture of a bevel-wheel, J, which is geared with a similar wheel, J', keyed on the shaft I' by means of wheels J².
- 20 On the surface of the core G of the vaporizing-chamber is formed a series of blades, e, which extend in longitudinal or vertical directions when the core is fixed, as in Fig. 1, and which are bent or curved, but in opposite direction to the blades of the driving-wheel C, as clearly shown in Fig. 6, when the core is 25 movable, as in Figs. 8 and 9.
- On the upper or outer portion of the shaft I or I' is mounted an eccentric, K, having a 30 rod, f, whereby it is connected to a rock-shaft, N, carrying the supply-valve B to the vaporizing-chamber, so that an oscillating motion is imparted to this valve by means of the shaft.
- The ways a of the supply-valve B are arranged in the arc of a circle of which the rock-shaft N is the center or axis, and hence such ways are alternately brought into play in the motion of the valve.
- In the condenser D is arranged an agitator, 40 P, consisting of bars which are attached either to the lower part of the shaft I, as in Fig. 1, or to the lower gudgeon, I², as in Fig. 8, and which carry arms h, projecting downwardly therefrom.
- 45 In applying the apparatus to use, bisulphide of carbon, together with steam or atmospheric air, or both, are admitted to the vaporizing-chamber A, wherein the bisulphide of carbon at once takes the form of vapor, which impinges against the blades of the driving-wheel C, and imparts to the latter a rapidly-revolving motion. The action of the steam admitted to the vaporizing-chamber A is to heat said chamber, and to increase the expansive properties of the bisulphide of carbon, while that of the air is to intensify such action. After the vapor has exerted its force on the driving-wheel C it escapes into the condenser D, wherein it is at once condensed or reliquefied, 55 together with the steam, and whence it escapes with the water through the pipes a'. The escape of the spent vapor from the vaporizing-chamber A to the condenser D is regulated by the cut-off F. The vapor is caused 60 to take a downward course in the vaporizing-chamber A, and is reflected upon the driving-wheel C through the medium of the vertical

channels formed therein by the blades d on the wall, and also by the blades e on the core of such chamber when the blades last named are 70 arranged as in Fig. 1.

When the blades e are bent or curved and the core of the vaporizing-chamber is arranged as in Figs. 8 and 9, the vapor has a like effect on the core as on the driving-wheel C, the motion of the core, however, being in an opposite direction to the driving-wheel.

The effect of the heating-chamber O is to prevent waste or loss of heat from the vaporizing chamber A by radiation, while the action 80 of the agitator P is to produce waves on the water flowing through the condenser D, and thus to increase its cooling-surface, a revolving motion being imparted to the agitator by its support.

85 It should be remarked that my apparatus is capable of other modifications than those herein described, one such modification being to make the block d^o and rod H and core G tubular, and the upper end of the core G perforated with small holes, so that the bisulphide of carbon or other liquid or vapor may be injected into the vaporizing-chamber A when the apparatus is arranged as in Fig. 1.

90 What I claim, and desire to secure by Letters Patent, is—

1. In a motor, the combination of a vaporizing-chamber, a driving-wheel fitted into such chamber, and a condenser communicating therewith, the whole constructed and adapted 100 to operate substantially as described.

2. In a motor, the combination of a vaporizing-chamber, a supply-valve to such chamber having triple ways, more or less, a driving-wheel fitted into the vaporizing-chamber, and a condenser communicating therewith, the whole constructed and adapted to operate substantially as described.

3. In a motor, the combination of a vaporizing-chamber, a driving-wheel fitted into such chamber, a condenser, and a cut-off interposed between the vaporizing-chamber and the condenser, the whole constructed to operate substantially as described.

4. In a motor, the combination of a vaporizing-chamber constructed with longitudinal or vertical blades on the wall thereof, a driving-wheel fitted into such chamber, and a condenser communicating therewith, the whole constructed and adapted to operate substantially as described.

5. In a motor, the combination of a vaporizing-chamber constructed with longitudinal or vertical blades both on the wall and the core thereof, a driving-wheel fitted into such chamber, and a condenser communicating therewith, the whole constructed and adapted to operate substantially as described.

In testimony whereof I have hereunto set my hand this 21st day of June, 1880.

BENJAMIN F. CARD.

In presence of—

SEYMOUR BURRELL,
PATRICK ROACH.
